CLAIM

The ornamental design for an implement for contacting surfaces, as shown and described.

DESCRIPTION

FIG. 1 is a perspective view of an implement for contacting surfaces ornamentation showing our new design;

FIG. 2 is a bottom view thereof;

FIG. 3 is a top view,

FIG. 4 is a right side view,

FIG. 5 is a left side view thereof;

FIG. 6 is a front view; and,

FIG. 7 is a back view.

The broken lines in the drawings are for illustrative purposes only and do not form a part of the claimed design.

1 Claim, 5 Drawing Sheets
